UNITED STATES PATENT OFFICE

CONSTANTINE SHIPSKI, OF OLYPHANT, PENNSYLVANIA

RAIL JOINT

Application filed May 20, 1930. Serial No. 454,114.

This invention relates to railroads and has especial reference to a rail joint.

One important object of the invention is to improve the general construction of such rail joints.

A second important object of the invention is to provide an improved form of rail joint wherein the meeting ends of rails may be secured together without the use of fish plates, chairs, tie plates or the like.

A third important object of the invention is to provide an improved form of such rail joint wherein the joint will be stronger than the body of a rail against vertical bending.

With the above and other objects in view, the invention consists in general of certain novel details of construction and combination of parts hereinafter fully described, illustrated in the accompanying drawings and specifically claimed.

In the accompanying drawings like characters of reference indicate like parts in the several views, and

Figure 1 is a plan view of the improved joint,

Figure 2 is a side elevation thereof,

Figure 3 is a section on the line 3-3 of Figure 2,

Figure 4 is a section on the line 4-4 of Figure 2,

Figure 5 is a section on the line 5-5 of Figure 2,

Figure 6 is an elevation, from the same direction as Figure 2, of the right hand rail in that figure,

Figure 7 is an elevation from the opposite side of the left hand rail of Figure 2.

The bodies of the two rails which meet to form this joint are of the usual general form having a head 10, web 11 and foot 12. At their meeting ends one of the rails has its web thickened along one side for a considerable distance as at 13 and this thickened portion is continued beyond the end of the rail body to form a tongue 14. The tongue has a height of such dimensions as to fit closely against the face of the web 11 of the other rail when the joint is assembled while at the same time bearing at its upper bevelled portion 15 against the underside of the head 10 of said

other rail. Also, the bevelled lower face 16 of this tongue fits closely on the upper surface of one side of the foot 12 of the meeting rail.

The remaining rail also has its web thickened for a considerable distance on the side opposite the tongue 14 as at 17 and the head 10 of this rail is also thickened as at 18 so that the side of the thickened head and the face of the portion 17 form a vertical wall 19. These thickened portions 17 and 18 are extended beyond the end of the rail body to form a tongue 20 which fits against the side of the first rail head and against the face of the first web. Also this tongue is shouldered along its upper inner portion as at 21 to fit snugly beneath the head of the first rail and has a bottom edge 22 bevelled to fit on one part of the foot 12 of the first rail.

The rail webs and tongues are provided with bolt holes 23 which upon assembly of the rails, register to receive the bolts 24 which are secured in position to hold the parts firmly together by nuts 25.

The rail feet are widened at the thickened portions and opposite the tongues and are provided with spike notches 26.

When assembled this joint is exceedingly strong and rigid and will not bend either vertically or laterally under the hardest usage.

There has thus been provided a simple and efficient device of the kind described and for the purpose specified.

It is obvious that changes may be made in the form and construction of the invention without departing from the principles thereof. It is not, therefore, desired to confine the invention to the exact form herein shown and described but it is desired to include all such as come within the scope claimed.

Having thus described the invention, what is claimed is:—

1. In a rail joint, a pair of abutting rails each having a web, a head and a foot, tongues laterally offset from the respective webs, and extending from each web along the side of the other web, and bolts securing said tongues and webs together, the head of one rail end being transversely thickened and having the

added thickness continued along the top of the tongue of said rail to lie against the side of the head of the other rail.

2. In a rail joint, a pair of abutting rails each having a web, a head and a foot, tongues laterally offset from the respective webs and extending from each web along the side of the other web, and bolts securing said tongues and webs together, each web being thickened 10 on the side opposite the tongue projecting from the other web, the head of one rail end being transversely thickened and having the added thickness continued along the top of the tongue of said rail to lie against the side 15 of the head of the other rail.
3. In a rail joint, a pair of abutting rails each having a web, a head and a foot, tongues laterally offset from the respective webs and extending from each web along the side of 20 the other web, and bolts securing said tongues and webs together, each tongue being shaped to bear beneath the head and on the foot of the other rail end, the head of one rail end being transversely thickened and having the added 25 thickness continued along the top of the tongue of said rail to lie against the side of the head of the other rail.

4. In a rail joint, a pair of abutting rails each having a web, a head and a foot, tongues 30 laterally offset from the respective webs and extending from each web along the side of the other web, and bolts securing said tongues and webs together, each tongue being shaped to bear beneath the head and on the foot of 35 the other rail end, each web being thickened on the side opposite the tongue projecting from the other web, the head of one rail end being transversely thickened and having the added thickness continued along the top of 40 the tongue of said rail to lie against the side of the head of the other rail.

5. In a rail joint, a pair of abutting rails each having a web, a head and a foot, tongues laterally offset from the respective webs, and 45 extending from each web along the side of the other web, and bolts securing said tongues and webs together, the head of one rail end being transversely thickened and having the added thickness continued along the top of 50 the tongue of said rail to lie against the side of the head of the other rail, the feet of said rails being laterally widened on both sides adjacent and at their meeting ends.

6. In a rail joint, a pair of abutting rails 55 each having a web, a head and a foot, tongues laterally offset from the respective webs and extending from each web along the side of the other web, bolts securing said tongues and webs together, each web being thickened on 60 the side opposite the tongue projecting from the other web, the head of one rail end being transversely thickened and having the added thickness continued along the top of the tongue of said rail to lie against the side of 65 the head of the other rail, the feet of said

rails being laterally widened on both sides adjacent and at their meeting ends.

7. In a rail joint, a pair of abutting rails each having a web, a head and a foot, tongues laterally offset from the respective webs and extending from each web along the side of the other web, bolts securing said tongues and webs together, each tongue being shaped to bear beneath the head and on the foot of the other rail end, the head of one rail end being transversely thickened and having the added thickness continued along the top of the tongue of said rail to lie against the side of the head of the other rail, the feet of said rails being laterally widened on both sides adjacent and at their meeting ends.

8. In a rail joint, a pair of abutting rails each having a web, a head and a foot, tongues laterally offset from the respective webs and extending from each web along the side of the other web, bolts securing said tongues and webs together, each tongue being shaped to bear beneath the head and on the foot of the other rail end, each web being thickened on the side opposite the tongue projecting from the other web, the head of one rail end being transversely thickened and having the added thickness continued along the top of the tongue of said rail to lie against the side of the head of the other rail, the feet of said rails being laterally widened on both sides adjacent and at their meeting ends.

In testimony whereof I affix my signature.

CONSTANTINE SHIPSKI.
